Primary Examiner — Sandra Morris(74) *Attorney, Agent, or Firm* — Scully, Scott, Murphy & Presser, P.C.(57) **CLAIM**

The ornamental design for a package for product, as shown and described.

DESCRIPTION

FIG. 1 is a perspective view of a package for product showing the first embodiment of my new design;

FIG. 2 is a front view thereof;

FIG. 3 is a rear view thereof;

FIG. 4 is a side view thereof;

FIG. 5 is an opposite side view thereof;

FIG. 6 is a top view thereof;

FIG. 7 is a bottom view thereof;

FIG. 8 is a perspective view of a package for product showing the second embodiment of my new design;

FIG. 9 is a front view thereof;

FIG. 10 is a rear view thereof;

FIG. 11 is a side view thereof;

FIG. 12 is an opposite side view thereof;

FIG. 13 is a top view thereof; and,

FIG. 14 is a bottom view thereof.

The portions indicated in broken lines are for illustrative purposes only and form no part of the claimed design.

1 Claim, 10 Drawing Sheets(56)
